UNITED STATES PATENT OFFICE.

FRED H. DOERING, OF SALIDA, COLORADO.

SLIDING GATE.

941,628.

Specification of Letters Patent. Patented Nov. 30, 1909.

Application filed June 11, 1909. Serial No. 501,573.

To all whom it may concern:

Be it known that I, FRED H. DOERING, a citizen of the United States, residing at Salida, in the county of Chaffee and State of Colorado, have invented certain new and useful Improvements in Sliding Gates; and I do declare the following to be a full, clear, and exact description of the invention, such as will enable others skilled in the art to 10 which it appertains to make and use the same.

This invention relates to improvements in sliding gates.

The object of the invention is to provide 15 a sliding gate having an improved construction of operating mechanism whereby the same may be readily opened and closed by a person riding in a vehicle or on horse back without alighting.

20 With the foregoing and other objects in view, the invention consists of certain novel features of construction, combination and arrangement of parts, as will be more fully described and particularly pointed out in 25 the appended claim.

In the accompanying drawings, Figure 1 is a perspective view of a gate showing the same in closed position; Fig. 2 is a side view showing the gate in partially open position.

30 Referring more particularly to the drawings, 1 denotes the supporting posts of the gate, on the upper ends of which is secured a track 2. The track 2 is raised at a point 35 adjacent to the upper end of the intermediate supporting post 1, as shown at 3, and inclines in opposite directions for a purpose hereinafter described.

On the track 2 is mounted a gate supporting frame 4, on the upper end of which is 40 arranged bearing brackets 5, on which are mounted track engaging wheels 6 by means of which the gate frame is slidably mounted on the track. On the lower end of the frame 45 4 is secured the gate 7 which may be of any suitable construction and has mounted on one side near its upper edge lever engaging wheels or rollers 8 and 9, between which is arranged the upper end of a gate operating 50 lever 10, the lower end of which is pivotally connected to the intermediate supporting post 1, as shown.

Connected to the upper end of the operating lever 10 are operating cords or cables 55 11 and 12 which extend upwardly and around guide pulleys 13 on a cross bar 14 se-

cured on the upper end of the intermediate supporting bar 1. On the outer ends of the operating cords 11 and 12 are suitable handles 15 and 16 by means of which the cords 60 are pulled to open or close the gate.

It will be noted that the inner bar of the gate supporting frame 4 is inclined so that the inner bearing bracket on the upper end of said bar will engage the track. 65

On one of the outer supporting posts 1 is arranged a latch keeper 17 which is here shown and is preferably in the form of a right angular plate and is adapted to be engaged by a latch 18 which is pivotally 70 mounted on one of the frame bars 4, adjacent to the outer end of the gate, as shown. The latch 18 is in the form of a bell crank lever with a right-angular arm depending from its lower leg. The arm terminates in 75 an upwardly inclined foot 21, which, when the gate is brought to a closed position, rides up on the latch keeper 17, carried by the post 1 until it drops by gravity behind the same, whereby the gate is automatically locked in 80 closed position.

To the inner upper end of the latch is secured an operating cord 22 which passes through a guide eye 23 and is connected to the end of the gate operating lever 10, 85 whereby when said lever is pulled upwardly by the operating cord to open the gate, the latch will be disengaged from the keeper.

In the operation of the gate, assuming the same to be in closed position, a person approaching the same from either direction, would grasp one of the handles 15 or 16 and pull the same, thus drawing upon either operating cord 11 and 12, which will pull the operating lever 10 upwardly into engagement with the wheel or roller 8, thereby sliding the gate back on its supporting track until the intermediate supporting wheel 6 on the track reaches the highest point 3 of the inclined portion of the track, at which time 90 the handle and operating cord are released allowing the momentum of the initial opening of the gate, together with the inclined portion of the track to carry the gate back to a complete open position. 100

105 It will be understood that in pulling upon the operating cords or cables, a sufficiently hard pull or jerk is given to the same to slide the gate back with considerable force until it is half way open, when upon the release of the operating cords, the momentum obtained from such jerk will completely open the gate, 110

as hereinbefore described. It will be understood that in closing the gate, the same operation is repeated.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention, as defined in the appended claim.

Having thus described my invention, what I claim is:

In a sliding gate, a supporting track, a

gate slidably mounted on said track, guide rollers arranged on said gate, a pivoted operating lever arranged between said guide rollers, operating cords connected to the upper end of said lever, a cord supporting cross arm, guide pulleys arranged on said arm to hold said cords in operative position, whereby the gate may be opened or closed from either side.

In testimony whereof I have hereunto set my hand in presence of two subscribing witnesses.

FRED H. DOERING.
